(57) **CLAIM**

The ornamental design for a LED lamp, as shown and described.

DESCRIPTION

FIG. 1 is a rear, right and bottom perspective view of a LED lamp, showing my new design;

FIG. 2 is a front, left and top perspective view thereof;

FIG. 3 is a perspective view thereof, shown in a used condition;

FIG. 4 is a front view thereof;

FIG. 5 is a rear view thereof;

FIG. 6 is a top plan view thereof;

FIG. 7 is a bottom plan view thereof;

FIG. 8 is a left side view thereof;

FIG. 9 is a right side view thereof; and,

FIG. 10 is an enlarged view of section 10 of FIG. 1.

The evenly-spaced broken lines shown in the drawings illustrate portions of the LED lamp that form no part of the claimed design. In FIGS. 1 and 10, the dash-dot-dash broken lines represent an enlarged sectional designation that forms no part thereof.
